D. S. BARROWS

CAR UNDERFRAME

Filed Aug. 2, 1922

UNITED STATES PATENT OFFICE.

DONALD S. BARROWS, OF ROCHESTER, NEW YORK, ASSIGNOR TO THE T. H. SYMINGTON COMPANY, OF NEW YORK, N. Y., A CORPORATION OF DELAWARE.

CAR UNDERFRAME.

Application filed August 2, 1922. Serial No. 579,223.

To all whom it may concern:

Be it known that I, DONALD S. BARROWS, a citizen of the United States, residing at Rochester, in the county of Monroe and 5 State of New York, have invented certain new and useful Improvements in Car Underframes; and I do hereby declare the following to be a full, clear, and exact description of the invention, such as will enable 10 others skilled in the art to which it appertains to make and use the same.

My invention relates to improvements in underframes for railway cars and, more particularly, to a strong, reliable and efficient metallic structure adapted to be applied generally to wooden underframe cars to reinforce the underframes thereof, thereby adapting said cars for use under modern service conditions.

20 To this end, one of the principal features of the invention, generally stated, is to provide a metallic structure, said structure being used to reinforce the car sills and designed to receive the buffing and pulling 25 shocks which are transmitted thereto by the draft rigging.

The invention, broadly stated, consists in providing a car underframe or draft arm in which the center sill reinforcing members 30 overlie the bolster and are connected thereto by means of an interposed gusset plate extending forwardly and rearwardly of the bolster, said gusset plate being connected to the inner ends of the draft sills.

35 Another object of the invention resides in the provision of a car underframe including in combination longitudinally arranged car sill reinforcing members adapted to overlie the bolster and having connected thereto depending draft members, a gusset plate bridging and connecting the reinforcing members and overlying the bolster, and means including a plurality of abutment members or blocks advantageously located 40 adjacent the front and rear portions of the bolster, said abutment members being adapted to effectively assist in resisting the strains to which the interconnected parts are subjected in service.

45 Another object of the invention is to provide a comparatively simple metallic structure for car underframes involving a single gusset plate bridging the center sill reinforcing members and connecting the same 50 to the bolster and to each other, said center

sill reinforcing members being further strengthened by means of filler plates preferably arranged in longitudinal alinement with the gusset plate and interposed between each reinforcing member and an adjacent 60 draft sill.

A further object of the invention is to provide a draft arm including in combination center sill reinforcing members adapted to be connected by a relatively long gusset 65 plate overlying the bolster and extending forwardly and rearwardly thereof, said reinforcing members being further connected by cross braces or tie members upon opposite sides of the bolster and near the ends 70 of said gusset plate.

There are other features of the invention as will be pointed out hereinafter in connection with the detailed description of my invention illustrated in the accompanying 75 drawings in which—

Figure 1 is a plan view of my improved metallic draft arm.

Figure 2 is a vertical central longitudinal sectional view through the construction 80 shown in Figure 1.

Figure 3 is a vertical transverse sectional view on the line 3—3 of Figure 2 viewed in the direction of the arrows.

Referring to the drawings in which similar reference characters designate corresponding parts in the several views, the wooden center sills of railway cars are adapted to be reinforced by means of longitudinally arranged angle members 1—1 85 adapted to overlie the bolster 2. The bolster is formed with upper flanges 3 and lower flanges 4, said flanges being connected by means of the web portion of the bolster, as shown. Braces or tie members 5 connect the reinforcing members, rivets 6 uniting the bent or flanged ends of said braces to the vertical flanges or center sill reinforcing members. Interposed between the upper flange of the bolster and the center sill reinforcing members is a gusset plate 7, said plate being preferably connected to the center sill reinforcing members by means of a plurality of rivets 8 and to the upper flanges 90 of the bolster by a plurality of bolts 9. 95

Arranged adjacent the forward edge of the upper flange of the bolster and centrally thereof, is an abutment member or block 10, said block being connected to the underside of the gusset plate by means of rivets 100 105

110

11. The ends of the block preferably extend beyond the vertical flanges of the center sill reinforcing members and are preferably located between the draft sills, as shown. Abutment members or blocks 12 are arranged immediately adjacent and contacting the rear edge of the upper flange of the bolster, each of said blocks 12 being connected to the horizontal flange of the center sill reinforcing members and interposed gusset plate by means of rivets 13. The abutment blocks 10 and 12 are advantageously positioned to resist the buffing and pulling shocks imparted to the underframe, and more particularly the center sill reinforcing members, the forward abutment block 10 having its end portions overlying the rear abutment blocks, as best shown in Figure 1.

20 The draft sills 14 are preferably of channel shape, the inner ends of said sills, and more particularly the inner upper flanges thereof being connected to a horizontal flange of the center sill reinforcing members and the interposed gusset plate 7 by some of the rivets 8 hereinbefore referred to. Interposed between the horizontal flange of each center sill reinforcing member and the upper flange of the adjacent 30 draft sill is a filler plate or strip 15, said filler strip being preferably positioned in longitudinal alinement with and forwardly adjacent the gusset plate 7. A plurality of rivets 16 preferably disposed in longitudinal 35 alinement with the rivets 8 serve to unite the filler member with the center sill reinforcing member and the adjacent draft sill. A bottom tie plate 17 connects the lower horizontal flanges of the draft sills, said tie 40 plate being secured to the draft sill flanges by means of rivets 18. The tie plate 17 is preferably located beneath the forward end of the gusset plate and spaced from the inner ends of the draft sills.

45 Cheek plates 19 are riveted to the faces of the draft sills, said cheek plates being provided with slots 20 adapted to register with slots in the draft sills for receiving a key of the well known Farlow draft rigging equipment, said key and rear block or follower being shown in dotted lines in Figure 2.

50 While I have for convenience illustrated the invention as applied to the three-key type of draft rigging, it will of course be apparent to those skilled in the art that the draft arm construction shown may be advantageously utilized with the more modern type of draft rigging illustrated, for 55 example, in the Symington Patent No. 1,097,738, issued May 26, 1914.

60 A draft arm constructed in accordance with my present invention permits the buffing and pulling loads to be effectively transmitted to the car center sills and the bolster,

the arrangement of abutment blocks and interposed gusset plate providing a simple, strong and easily assembled connection. I have described my invention in detail so that its nature and the manner of using it may be fully understood by those skilled in the art. However, the specific terms herein are used in their descriptive sense rather than in their limiting sense, and the scope of the invention is defined in the 75 claims.

I claim:

1. In a car underframe, the combination with center sills and bolster, of center sill reinforcing members adapted to be connected to the center sills, draft sills connected to and arranged beneath the center sill reinforcing members, a gusset plate interposed between the center sill reinforcing members, the bolster and the inner ends of said draft sills, and strengthening means involving abutment blocks arranged adjacent the bolster and connected to said gusset plate. 80

2. In a car underframe, the combination with center sills and bolster, of center sill reinforcing members adapted to be connected to the center sills, draft sills having their inner ends arranged in close proximity to the forward edge of the bolster, means connecting said draft sills to the center sill reinforcing members, and a gusset plate, said gusset plate being arranged to overlie the bolster and provided with a plurality of abutment blocks one of which is arranged between the draft sills. 90

3. In a car underframe, the combination with center sills and bolster, of center sill reinforcing means, draft sills, connecting means interposed between and uniting the center sill reinforcing members, bolster and draft sills, and abutment means provided between said connecting means and bolster. 105

4. In a car underframe, the combination with center sills and bolster, of center sill reinforcing means, draft sills, connecting means interposed between and uniting the center sill reinforcing members, bolster and draft sills, and strengthening means including abutment members arranged on opposite 110 sides of the bolster.

5. In a car underframe, the combination with center sills and bolster, of center sill reinforcing means, draft sills, connecting means interposed between and uniting the center sill reinforcing members, bolster and draft sills, and strengthening means including an abutment member arranged adjacent the upper flange of the bolster. 120

6. In a car underframe, the combination with center sills and bolster, of center sill reinforcing means, draft sills, connecting means interposed between and uniting the center sill reinforcing members, bolster and draft sills, and abutment means arranged 125 130

between said connecting means and bolster, said abutment means including a block member positioned adjacent the forward portion of the bolster between the draft sills and

5 another block member arranged adjacent the rear portion of said bolster.

7. In a car underframe, the combination with center sills and bolster, of center sill reinforcing means, draft sills, connecting

10 means interposed between and uniting the center sill reinforcing members, bolster and draft sills, and abutment means including block members arranged adjacent the forward and rear portions of said bolster, the

15 forwardly arranged abutment block having portions overlying the rearwardly positioned abutment blocks.

8. In a car underframe, the combination with center sills and bolster, of center sill 20 reinforcing means, draft sills, connecting means interposed between and uniting the center sill reinforcing members, bolster and draft sills, and abutment means including a centrally located member adjacent the forward edge of the bolster, and spaced members arranged adjacent the rear edge of the bolster.

9. In a car underframe, the combination with center sills and bolster, of center sill 30 reinforcing means, draft sills, connecting means interposed between and uniting the center sill reinforcing members, bolster and draft sills, and abutment means including a centrally located member adjacent the forward edge of the bolster and spaced members arranged adjacent the rear edge of the bolster, the said last named members having portions overlying the forwardly and centrally located member.

40 10. In a car underframe, the combination with center sills and bolster, of center sill reinforcing means, draft sills, connecting means interposed between and uniting the center sill reinforcing members, bolster and draft sills, abutment members arranged adjacent the rear edge of the bolster and longitudinally alined with said draft sills, and an abutment member arranged adjacent the forward edge of said bolster between the draft sills.

50 11. In a car underframe, the combination with center sills and bolster, of center sill reinforcing means, draft sills, a gusset plate overlying the bolster and adapted to extend forwardly and rearwardly thereof between the center sill reinforcing means and the inner ends of said draft sills, rivet means connecting said gusset plate, draft sills and re-

inforcing members, and filler strips interposed between said draft sills and adjacent 60 reinforcing members forwardly of the bolster.

12. In a car underframe, the combination with center sills and bolster, of center sill 65 reinforcing means, draft sills, a gusset plate overlying the bolster and adapted to extend forwardly and rearwardly thereof between the center sill reinforcing means and the inner ends of said draft sills, rivet means connecting said gusset plate, draft sills and 70 reinforcing members, and filler members interposed between the draft sills and reinforcing members, said filler members being arranged in longitudinal alinement with said gusset plate and being connected to the draft 75 sills and center sill reinforcing members.

13. In a car underframe, the combination with center sills and bolster, of center sill reinforcing means, draft sills, a single gusset plate overlying the bolster and connecting 80 the draft sills and center sill reinforcing members, filler strips interposed between the draft sills and reinforcing members, and a tie plate connecting the draft sills beneath the forward end of the gusset plate. 85

14. In a car underframe, the combination with car sills and bolster, reinforcing members adapted to be connected to said car sill, a gusset plate overlying the bolster, and means including connecting braces uniting 90 the reinforcing members, said braces being located near the forward and rear ends of the gusset plate.

15. In a car underframe, the combination with car sills, of means reinforcing said car 95 sills, draft sills arranged beneath said reinforcing means, cheek plates connected to said draft sills, and a gusset plate interposed between the reinforcing means and draft sills, said gusset plate being adapted to overlie the 100 bolster and having its forward end extending adjacent said cheek plates.

16. In a car underframe, the combination with car sills, of means reinforcing said car 105 sills, draft sills arranged beneath reinforcing means, cheek plates connected to said draft sills, a gusset plate interposed between the reinforcing means and draft sills, said gusset plate being adapted to overlie the bolster and having its forward 110 end extending adjacent said cheek plates, and a tie plate connecting the draft sills beneath the forward end of the gusset plate and the rear end of said cheek plates.

In testimony whereof I affix my signature.
DONALD S. BARROWS.
